(57) **CLAIM**

The ornamental design for a banknote counter, as shown and described.

DESCRIPTION

FIG. 1 is a perspective view of a banknote counter with the shutter shown in a closed position;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear elevational view thereof;

FIG. 7 is a bottom plan view thereof; and,

FIG. 8 is a perspective view of a banknote counter with the shutter shown in an open position.

The portions of the banknote counter shown in broken lines form no part of the claimed design.
